Attorney.

said waist band being adapted to pass twice about the waist of the infant, the opposite end portion of said band being adapted to be threaded successively through said slits, and the end portions of said waist band being adapted to be 5 adjustably connected at the back of the infant.

2. A diaper comprising a body member adapted to be secured about the body of an infant, a waist band secured along an edge of said body member and adapted to pass twice about the 10 waist of said infant and having a plurality of slits formed therein adjacent one end thereof, and adjustable means for joining the opposite ends of said band at the back of the infant, one end portion of said band being threaded successively through said slits, thus interengaging the overlapping portions of the band. 15

3. A diaper comprising a body member adapted to be secured about the body of an infant, a waist band secured along an edge of said body member and adapted to pass twice about the 20 waist of said infant, and adjustable means for joining the opposite ends of said band at the back of the infant, one end portion of said band being threaded through a slit provided therefor through said band at the front of the infant, and through a second slit provided therefor ad- 25

jacent the opposite end of the waist band, thereby interengaging the overlapping portions of the waist band at the front and back of the infant.

MARY E. BRINK.
